T. BILLINGTON

CLAMP

Filed April 9, 1923

Witness

Inventor

T. Billington.

Attorneys

UNITED STATES PATENT OFFICE.

THEOPHILUS BILLINGTON, OF CLEARWATER, FLORIDA.

CLAMP.

Application filed April 9, 1923. Serial No. 330,891.

To all whom it may concern:

Be it known that I, THEOPHILUS BILLINGTON, a citizen of the United States, residing at Clearwater, in the county of Pinellas and State of Florida, have invented certain new and useful Improvements in Clamps; and I do declare the following to be a full, clear, and exact description of the invention, such as will enable others skilled in the art to which it appertains to make and use the same.

My invention relates to improvements in work clamps and has for its object to provide an extremely simple and inexpensive construction which will be highly efficient and desirable and may be readily adjusted within a wide range.

With the foregoing in view, the invention resides in the novel subject matter herein-after described and claimed, the description being supplemented by the accompanying drawing.

Figure 1 is a side elevation of a clamp constructed in accordance with my invention.

Figure 2 is a central longitudinal sectional view.

Figure 3 is a transverse sectional view as indicated by line 3—3 of Fig. 1, showing the movable jaw of the clamp secured in adjusted position.

Figure 4 is a view similar to Fig. 3 but illustrating the movable jaw released.

Figures 5 and 6 are sectional views on lines 5—5 and 6—6 of Fig. 1.

In the drawing above briefly described, the numeral 1 designates a straight shank preferably having a widened base portion 2, the front end of this shank being directed upwardly to form a bearing 3 through which a screw 4 is threaded for adjusting a jaw 5 whose lower end is formed with a groove 6 receiving the upper edge of the shank 1.

A relatively movable jaw 7 is provided with an opening 8 through which the shank 1 passes to permit said jaw to be adjusted along the shank. Below the shank, the jaw 7 is provided with a yoke 9 which preferably consists of a front plate 10, a rear plate 11, and a bottom plate 12 connecting the lower edges of said plates 10 and 11. A cam 13 is received in the yoke 9 and when turned in one direction, is adapted to wedge between the shank 1 and the bottom plate 12, thus securing the movable jaw 7 in any position to which it has been moved. Al-

though not absolutely essential, I prefer to provide the cam 13 and the shank 1, with co-operating teeth 14 and 15.

A longitudinal shaft 16 is provided under the shank 1 for rotating the cam 13, this shaft being preferably of the square cross-section shown. The shaft passes slidably through an opening 17 in the cam 13 and extends loosely through circular openings 18 in the front and rear plates 10 and 11 of the yoke 9, the front end of said shaft being slidably and rotatably received in a bearing 19 which depends from the front end of the shank 1, while the rear end of said shaft is swiveled at 20 in a bearing 21 having a slide portion 22 which engages the widened base 2 of the shank 1. The front end of the shaft 16 is provided with an operating handle 23 for operating the cam 13 and it will be seen that by pulling forwardly upon this handle, the slide 22 will strike the yoke 9 and will consequently shift the movable jaw 7 forwardly to any desired extent. Thus, the jaw may be brought up against the work and by then turning the shaft in the proper direction, the cam 13 will wedge between the plate 12 of the jaw 7 and the shank 1, thereby tightly holding said jaw in place. This having been done, the shaft 16 may be slid rearwardly out of the way and by operating the screw 4, it will be seen that the jaw 5 is made to co-operate with the jaw 7 in tightly clamping the work.

By providing the construction shown or a substantial equivalent thereof, it will be obvious that a very simple and desirable clamp has been provided and furthermore, it will be seen that by making slight changes the clamp might be adapted for use as a vise.

I claim:

1. A clamp comprising a shank having a relatively stationary jaw adjacent its front end, said front end of the shank having a bearing at the side of the shank opposite said jaw, a relatively movable jaw slidable along said shank and having a yoke at the last named side thereof, a rotatable cam in said yoke to wedge between a portion of the latter and said shank and hold said movable jaw in adjusted position, and a shaft for turning said cam, said shaft extending rotatably through the aforesaid bearing and having a handle at its front end.

2. A clamp comprising a shank having a relatively stationary jaw adjacent its front end, said front end of the shank having a

bearing at the side of the shank opposite said jaw, a relatively movable jaw slidable along said shank and having a yoke at the last named side thereof, a rotatable cam in said yoke to engage said shank and hold the movable jaw in adjusted position, a shaft for rotating said cam, said shaft passing slidably through said cam and slidably and rotatably through the aforesaid bearing, a second bearing in which the rear end of the

shaft is swiveled, means mounting said second bearing on said shank for sliding along the latter, and a handle on the front end of said shaft for pulling it forwardly to similarly move the movable jaw and for rotating said shaft to operate said cam. 15

In testimony whereof I have hereunto affixed my signature.

THEOPHILUS BILLINGTON.
